UNITED STATES PATENT OFFICE.

THOMAS L. RIVERS, OF MONTCLAIR, ASSIGNOR OF ONE-THIRD TO JOSEPH-
INE THOMAS, OF NEWARK, NEW JERSEY.

HAME-TUG.

SPECIFICATION forming part of Letters Patent No. 319,126, dated June 2, 1885.

Application filed November 10, 1884. (No model.)

To all whom it may concern:

Be it known that I, THOMAS L. RIVERS, a citizen of the United States, residing at Montclair, in the county of Essex and State of New Jersey, have invented a new and useful Improvement in Hame-Tugs, of which the following is a specification, reference being had to the accompanying drawings.

My invention relates to hame-tugs.

10 Heretofore in the construction of hame-tugs attempts have been made to provide against the accidental detachment of the sections in various ways; but as yet this result has not been effectually accomplished.

15 My invention has for its object to provide a hame-tug consisting of a series of sections so connected that there will be no possible chance of the said sections becoming accidentally separated or detached.

20 A further object of the invention is to provide improved means for connecting the hame-tug with the hame of the harness, and to provide means of such construction that the hame-tug may be easily and quickly attached to or 25 detached from the hame, and yet will be held against accidental detachment therefrom.

A further object of the invention is to provide a trace guide-loop or carrier with an extension whereby the trace will be held in position and its vertical movement or play limited, and thus relieve the hame-section to which it is connected of any strain to which it might be subjected by the vertical movement of the trace.

30 A further object of the invention is to provide improved means for connecting the trace guide-loop or carrier with one of the sections composing the tug, while a still further object of the invention is to provide a hame-tug 35 which shall be cheap and simple in its construction, and one that will be strong and durable.

With these ends in view the invention consists, primarily, in the improved manner of 40 connecting the sections composing the tug.

The invention further consists in the combination, with a hame-tug, of a plate hinged thereto and a pivoted sectional clip connected to said plate.

45 The invention further consists in the improved construction of trace guide-loop or

carrier and in the means of connecting the same with the tug, hereinafter fully described, and pointed out in the claims.

The invention further consists in the details 55 of construction and combination of parts, hereinafter fully described, and pointed out in the claims.

In the drawings, Figure 1 is a side elevation of a hame-tug constructed in accordance with 60 my invention, showing the plate carrying the pivoted sectional clip connected therewith, also showing the trace guide-loop or carrier connected with the hame-tug. Fig. 2 is a perspective view of two of the hame-sections 65 and their connecting-link detached, one of said sections and the link being inverted. Fig. 3 is a perspective view of the plate carrying the pivoted sectional clip, said clip being shown open. Fig. 4 is a perspective view of the 70 trace carrier or guide-loop detached; and Fig. 5 is a longitudinal vertical section of two of the hame-sections and link, showing the same connected.

In the accompanying drawings, in which 75 like letters of reference indicate corresponding parts in all the figures, A represents a hame-tug constructed in accordance with my invention.

B represents the hame-sections. The hame-sections are beveled or cut off obliquely at their ends, so that said sections may be flexible, and be allowed a hinge movement, which could not be obtained if the sections were formed square at their ends. Near each end 85 of the sections B are formed rectangular slots a, the sides of which are beveled or inclined downwardly, as shown at b. At about the center of each section B is formed a raised portion, c, having an oblong slot, d, at the rear end of 90 which and in one corner of the same is formed a small extended opening, e. The oblong opening on the sections is formed for the purpose of attaching the lug on the trace-plate, as will be hereinafter more fully described; 95 but it will be seen that, if desired, said opening might be omitted from all the sections with the exception of the rear one, to which the said lug is attached. I prefer, however, to form each of the sections with said opening 100 for the reason that the tug may be lengthened and shortened at will, and the said lug on the

trace-plate attached to any one of the sections. In addition to this advantage, forming the sections with the oblong openings makes the same considerably lighter, which is an important point, as the sections are constructed of metal. Upon the under sides of the sections B at each end of the same are provided recesses f, which form seats for the body portion of the connecting-links C, said body portions resting in the seats, which prevent or hold the sections against flexion in a vertical direction. The connecting-links consist of the body portion formed at its ends with upwardly-extending lugs f' having side flanges, g, which, when the links C are in engagement with sections, bear or rest in seats formed by making the sides of the openings for the reception of the same inclined. The ends of the said links C incline upwardly in order that they may have an outward movement to allow flexion in this direction of the sections, and also to allow of the attachment and detachment of the links, which could not be accomplished if the links were formed with straight ends. In connecting the sections the end of the link is turned, so that it will be parallel with the slots, and inserted in one of said slots from the under side thereof, the said link is then turned to the position shown in Figs. 1 and 5. The next section is attached to the other end of the link in the same manner, and so on until a sufficient number of links have been connected.

D represents a plate, which is formed at its rear end with a rearwardly-extending lug of the same form as those upon the connecting-links. At the other end of the plate are formed two forwardly-extending lugs provided with holes or openings h. Upon a bolt, i, bearing in the openings h of the lugs, is pivoted a sectional clip, E, which consists of the two curved sections j, reduced on their inner sides near their lower ends. By the use of this clip the sections may be readily opened and engaged with a ring in the hame, and then closed. When draft is applied, they will be securely held against detachment.

F represents the guide-loop or trace-carrier, which has at its forward end a lug, k, of the same form as those upon the connecting-links. Loops l² are provided one on the upper and the other on the lower end of the carrier F, for the passage of the belly-band, which holds said carrier in position. At the rear end of the carrier are provided two rearwardly-projecting extensions connected at their upper ends, and projecting rearwardly from these lugs is an extension, m. The loop formed by the upwardly-extending lugs connected at their upper ends serves to hold the trace in position and limit its vertical play, while the extension holds the trace on a line with the hame-tug. A trace-plate, G, is secured to the end of the trace, (not shown,) said plate being provided on its under side with a lug of the same form as the oblong openings of the hame-sections.

From the foregoing it will be seen that a

hame-tug constructed as above described is simple, cheap, and durable, that the sections cannot be accidentally detached, and that by 70 the use of the trace-carrier above described the trace is held in position against vertical movement.

Having fully described my invention, what I claim as new, and desire to secure by Letters Patent, is—

1. In a hame-tug, the sections having beveled ends and rectangular openings near said ends, in combination with detachable connecting-links having attaching-lugs, substantially 80 as set forth.

2. In a hame-tug, the combination, with the sections having rectangular openings at their ends, the sides of which incline inwardly, and seats upon the under sides of said sections at 85 each end, of links connecting said sections, as set forth.

3. In a hame-tug, the sections having a central elongated opening, rectangular openings at their ends, said rectangular openings having inclined sides, seats on the under sides of said sections, said sections having beveled ends, in combination with connecting-links, as set forth.

4. The combination, with the hame-sections, 95 of connecting-links having lugs at each end, said lugs having inclined end faces and adapted to interlock with the slotted ends of the sections, substantially as set forth.

5. The combination, with the hame-sections, 100 of connecting-links having lugs at their ends, provided with side flanges, and being also provided with inclined end faces, as set forth.

6. In a hame-tug, a plate having a lug at one end and a sectional clip at its other end, 105 in combination with a series of detachable hame-sections, substantially as set forth.

7. In a hame-tug, a plate having a lug at one end and a sectional clip at its other end, 110 said lug having side flanges, as shown, in combination with the hame-sections, as set forth.

8. In a hame-tug, a trace-carrier having an extension at its rear end and a lug at its other end, in combination with the hame-sections, 115 substantially as and for the purpose set forth.

9. In a hame-tug, a trace-carrier having a lug at one end and a guide-loop at its other end, in combination with the hame-sections.

10. In a hame-tug, a trace-carrier having 120 a lug at one end and a loop and extension therefrom at its other end, in combination with the hame-sections, as set forth.

11. In a hame-tug, detachable sections connected by links having upwardly-extending 125 lugs, a trace-carrier attached to the rear section, and attaching means, substantially as described, connected with the forward section.

In testimony that I claim the foregoing as my own I have hereto affixed my signature in presence of two witnesses.
